DESIGN FOR A COMBINED GAME AND ASH TRAY

Helen Webber, New York, N. Y.

Application May 22, 1941, Serial No. 101,083

Term of patent 7 years

To all whom it may concern:

Be it known that I, Helen Webber, a citizen of the United States, residing in the city and State of New York, county of Bronx, have invented a new, original, and ornamental Design for a Combined Game and Ash Tray, of which the following is a specification, reference being had to the accompanying drawing, forming a part thereof;

Fig. 1 is a top plan view of a combined game and ash tray showing my new design.

Fig. 2 is a side elevational view thereof.

The article comprises an ash tray upon which is rotatably mounted the spherical dome.

I claim:

The ornamental design for a combined game and ash tray, substantially as shown and described.

HELEN WEBBER.
